[57] CLAIM

The ornamental design for a cord take-up reel, as shown and described.

DESCRIPTION

FIG. 1 is a left side and front perspective view of a cord take-up reel, showing my new design;

FIGS. 2 and 3 are respectively front and rear elevational views thereof;

FIGS. 4 and 5 are respectively top and bottom plan views thereof;

FIGS. 6 and 7 are respectively left and right elevational views thereof;

FIG. 8 is a sectional view taken along the line 8—8 of FIG. 2;

FIG. 9 is a sectional view along line 9—9 in FIG. 6; and,

FIG. 10 is a sectional view taken along line 10—10 in FIG. 2.
